United States Patent Office

Des. 196,411
Patented Sept. 24, 1963

196,411

RELAXING MACHINE

Alvin Charles Larson, 427 E. Capitol Drive,
Pewaukee, Wis.

Filed Aug. 22, 1962, Ser. No. 71,414

Term of patent 3½ years

(Cl. D83—1)

FIG. 1

FIG. 2

FIG. 1 is a front perspective of a relaxing machine showing my new design, the rear not shown is substantially the same as the front; and

FIG. 2 is a view looking at one end thereof, the opposite end being identical.

I claim:

The ornamental design for a relaxing machine, substantially as shown and described.
